UNITED STATES PATENT OFFICE.

THOMAS H. ROSS, OF BROOKLYN, NEW YORK, ASSIGNOR, BY DIRECT AND MESNE ASSIGNMENTS, TO ARCAS BRASS AND IRON COMPANY, INC., OF NEW YORK, N. Y., A CORPORATION OF NEW YORK.

HAIR CURLER OR WAVER.

Application filed May 9, 1923. Serial No. 637,684.

To all whom it may concern:

Be it known that I, THOMAS H. Ross, a citizen of the United States, and resident of borough of Brooklyn, in the county of 5 Kings and State of New York, have invented certain new and useful Improvements in Hair Curlers or Wavers, of which the following is a specification.

This invention relates to hair curlers or 10 wavers of the class wherein the device consists of a pair of connected spring arms that are normally divergent, in which condition a strand of hair is to be wrapped about one arm, and then the pair of arms are 15 pressed together and secured by suitable engaging means for a period during which the wrapped hair becomes set into a formed curl or wave.

My present improvement, directed to this 20 character of hair curler or waver includes the provision of novel engaging means between the spring arms, whereby the device may be more conveniently operated, and it also includes certain structural features 25 whereby the hair curling or waving produced by its use, is more effective than with other devices of the same class, besides being less likely to cut or injure the hair.

With these and other objects in view my 30 invention consists of a strip of flat metallic material, of spring-like character, folded to provide two divergent arms, with the fold comprising a tensional joint, one of the arms having inturned lateral portions, to thus 35 provide rounded edges, and its free end being bent or rolled over in the form of a hook; whilst the other arm, which may be shaped into a tube, and is adapted to have a strand of hair wrapped thereon is of 40 such shorter length that its free end may be snapped under the hook of the longer arm, when pressed in the direction thereof, to thereby lock the arms together for the performance of the hair curling or waving 45 operation.

Other features and advantages of my invention will hereinafter appear.

In the drawings:

Fig. 1 is a vertical front view of my 50 improved hair curler or waver, in the closed position.

Fig. 2 is a section on the line 2—2 of Fig. 1.

Fig. 3 is a side elevation of the device, in its closed position, 55

Fig. 4 is a side elevation, showing the device open, and

Fig. 5 is a side elevation of the device, showing it in the closed position with a strand of hair engaged thereby in process 60 of curl or wave formation.

In carrying out my invention I take a strip of thin sheet metallic material, of spring-like character, and shape or fold it to provide the joint or heel 1 and the normally divergent arms 2, 3. 65

The arm 2, which is shorter than arm 3 is, by a suitable formative process, made tubular or cylindrical for the greater portion of its length. This arm 2 is intended to 70 have wrapped about it a strand or lock of hair which is to be curled or waved. The arm 3, which is left flat, has lateral portions 4, 4 thereof folded over upon its inner surface, to thereby afford a rounded contour 75 for the edges 5, 5 which are thus provided. Also, by means of the folded over lateral portions 4, 4, which each occupy a relatively narrow space upon the inner surface of arm 3, there is left an intermediate surface portion thereon in the form of a central depression or channel 6. This channel is opposed to the arm 2, so that when the arm 2 is wrapped with hair, and fastened, that portion of the hair caught between the 80 arms 2 and 3 becomes crimped by reason of its being pressed into the channel.

The fastening means between the arms is provided by means of a hook-like formation 7 at the free end of arm 3. In the example 90 of this fastening means shown in the drawings it appears in partly cylindrical or rolled over shape, the end of the hook approaching, but lying in spaced relation to the inner surface of the arm, and the clearance intervening being sufficient in extent 95 for the reception of the arm 2. It is essential that the outer surface of the hook 7 shall present an incline 8 which slopes downwardly in the direction of the heel of 100 the device, and lies in the inward or closing path of the arm 2, at the extreme free end of the latter. In fact the length of arm 2 is just sufficient to enable it, in closing, to 105 strike against incline 8, and then, under pressure, to slightly displace the hook until

cleared, whereupon the hook will snap back into its normal position, in which it then engages the extreme end of arm 2 and locks said arm in the closed position.

5 It is only when the device is out of service that so slight an extent of the arm 2 is caught by the hook, because, when a quantity of hair is wrapped about arm 2, and then the arms 2 and 3 are pressed together 10 and locked, the bulk provided by the hair lying between the arms causes the arm 3 to bulge outwardly, which has the effect of shortening its length relatively to its normal length, and thereby the hook will overhang 15 a greater extent of arm 2 when snapped thereon, thus rendering the lock more secure. In fact the lock becomes stronger in proportion to the extent of the load imposed thereon, as the quantity of hair gripped between 20 the arms is increased.

It should be particularly noted that with this device, locking thereof is performed by the action of pressing one arm directly toward the other arm, whereupon an automatic snap fastening effect is provided, and that this is easily done with one hand.

To release the lock the arm 2 is pressed sideways until its free end leaves engagement with hook 7. This operation is facilitated by the cylindrical form of arm 2, which thus presents ample surface for the employment of laterally applied pressure thereon, as by the thumb of the user.

It will be appreciated that relatively thin 35 stock may be employed in the manufacture of this device, because both the arms 2 and 3 are stiffened in their structural formation, the arm 2 because it is made cylindrical, and the arm 3 because of its marginal folded over portions. Also the hook 7, which is required to possess a degree of spring tension, is stiffened sufficiently therefor by the 40 marginal folded over portions.

Variations within the spirit and scope of 45 my invention are equally comprehended by the foregoing disclosure.

I claim:

1. A hair curler or waver composed of a single strip of spring-like material, bent into 50 two, normally divergent, straight arms of unequal length, the shorter arms, which is to be wrapped with hair being cylindrical to render it stiff and unyielding, and the longer arm being longitudinally flexible and being 55 relatively flat, with folded over lateral portions to reinforce it, leaving an intermediate channel, and said longer arm having a

curved, inturned hook whose outer surface provides an inclined guide opposed to the end of the shorter arm in closing the arms together, the hook end being opposingly spaced from the inner surface of the longer arm, and capable of yielding sufficiently under closing pressure to permit the end of the shorter arm to snap past the hook for 60 engagement. 65

2. A device of the kind described composed of a single strip of resilient material of substantially uniform width throughout, said strip being doubled intermediate its 70 ends to provide a longer and a shorter arm the portion of the strip forming the shorter arm being laterally formed to constitute a substantially closed circular tube, the portion forming the longer arm having its lateral edges inturned to provide smoothly rounded and reinforced edges, the free ends of the arms being provided with interlocking 75 elements.

3. A device of the kind described composed of a single strip of resilient material of substantially uniform width throughout, said strip being doubled intermediate its 80 ends to provide a longer and a shorter arm the portion of the strip forming the shorter arm being laterally formed to constitute a substantially closed circular tube, the portion forming the longer arm having its lateral edges inturned to provide smoothly rounded and reinforced edges, the free ends 85 of the arms being provided with interlocking elements, one of which constitutes a guide for the other in closing the arms together. 90

4. A device of the kind described composed of a single strip of resilient material of substantially uniform width throughout, said strip being doubled intermediate its 95 ends to provide a longer and a shorter arm, the portion of the strip forming the shorter arm being laterally formed to constitute a substantially closed circular tube, the portion forming the longer arm having its lateral edges inturned to provide smoothly rounded 100 and reinforced edges, the free end of the longer arm having a hook shaped formation to form a guide for the shorter arm in closing said arms together, whereby said shorter arm enters into snap lock engagement with 105 said longer arm. 110

Signed at the borough of Manhattan, in the city, county, and State of New York, this 5th day of May, A. D. 1923.

THOMAS H. ROSS.
